[57] ABSTRACT

A detergent bar including a major amount of anhydrous water-soluble higher fatty acid soap and a minor amount of a water-soluble synthetic detergent chosen from the group including fatty ester amides of sulfoxuccinic acid.

6 Claims, No Drawings

SOAP BARS

The invention relates generally to detergent bars having improved curd dispersing properties as well as good lathering performance. More specifically, the invention is concerned with detergent bars, comprising a combination of a soap and a curd dispersing synthetic detergent, that are firm, non-tacky and pleasant to use.

It is well known that when ordinary toilet soap is used in hard water, i.e., water with a relatively high concentration of magnesium and calcium metals, the formation and precipitation of an insoluble scum or curd usually results. This curd, commonly known as lime soap, includes coagulated, insoluble fatty acid salts and is commonly observed in wash basins or bathtubs as a scum that adheres to the walls as an unsightly ring.

It has been suggested that soap and a synthetic detergent having lime soap dispersing properties be combined in bar form to prevent the formation of the very undesirable lime soap curds. However, the use of large amounts of synthetic detergent in combination with soap, generally results in the impairment or elimination of desirable soap properties such as lathering performance, firmness and non-tackiness. Additionally, the inclusion of large amounts of synthetic detergent in soap bars usually results in manufacturing difficulties and a substantially increased cost.

In accordance with the invention, a new synthetic detergent is provided, which when combined with soap in predetermined amounts produces a combination bar exhibiting a substantially reduced tendency to form lime soap curds when used in hard water. Additionally, the new combination bars retain good lathering performance, are non-tacky and pleasant to use.

The kind of soap used in preparing the improved combination soap-detergent bar is not critical and should not be considered a limitation of the invention. Any of the water-soluble soaps, derived from animal or vegetable fatty acids, and formulated for industrial, household and toilet use may be employed. Water-soluble soaps such as the sodium, potassium and other suitable alkali metal or ammonium soap or soaps of nitrogen bases, such as triethanolamine, derived from fats and oils such as cottonseed oil, soybean oil, corn oil, olive oil, palm oil, palm kernel, lard, greases, fish oils and the like, as well as their hydrogenated derivatives; and mixtures thereof, that are properly blended to yield the desired soap quality may be used in formulating the soap portion of the new combination bars.

In accordance with the invention, the new detergent bar includes a synthetic detergent component of up to about 30 percent by weight. More specifically the synthetic detergent component of the improved bar includes fatty ester amides of sulphosuccinic acid having the following alternative structures:

wherein:

M is chosen from those positive metals and groups which produce water-soluble salts of the sulfosuccinate amide, including the alkali metals sodium and potassium, hydrogen, ammonium or organic bases such as ethanolamine, alkaloid, etc.

R₁ is hydrogen or a C₁₂ to C₂₀ saturated or unsaturated fatty chain;

R₂ is a C₁ to C₄ aliphatic chain; and
R₃ is hydrogen or a C₁₁ to C₁₉ saturated or unsaturated fatty chain, and
R₁ and R₃ cannot both be hydrogen.

5 Although the monoester derivative is preferred in practicing the invention, i.e., wherein R₁ is hydrogen; significant quantities of the diester as well as free alcohol and free alcohol amide can be present.

In further accordance with the invention, it is preferred to use sperm oil monoalkylolamide sulphosuccinate as the synthetic detergent ingredient of the new bars. Sperm oil monoethanolamide sulphosuccinate which is a mixture of components of the above described structure wherein M is sodium, R₁ is H, C₁₆H₃₃, or C₁₈H₃₅, plus minor amounts of other fatty chains; R₂ is —C₂H₄— and R₃ is C₁₅H₂₉, C₁₇H₃₃ or C₁₉H₃₇ plus minor amounts of other aliphatic chains is preferred. The foregoing sperm oil derivatives are mainly monoester but significant quantities of di-ester, free alcohol and free alkyl ethanolamide would be expected as well.

20 Sperm oil monoalkylolamide sulphosuccinates can be synthesized from sperm oil, which is R₃COOR₁ wherein R₁ is a C₁₂ to C₂₀ saturated or unsaturated fatty chain (mainly C₁₆H₃₃ and C₁₈H₃₅) and R₃ is a C₁₁ to C₁₉ saturated or unsaturated fatty chain (mainly C₁₅H₂₉, C₁₇H₃₃ and C₁₉H₃₇, as follows sperm oil is reacted with an alkylolamine of the general formula HOR₂NH₂ wherein R₂ is C₂H₄, C₃H₆ or C₄H₈ to give a fatty alkylolamide of the formula R₃CONHR₂OH and a fatty alcohol, R₁OH. The fatty alkylolamide and fatty alcohol mixture is reacted with maleic anhydride to give sperm oil monoalkylolamide maleate, which has the following structure:

25 One of either R₁ or R₃ can be hydrogen. The sperm oil monoalkylolamide maleate mixture is then reacted with alkali bisulphite MH SO₃ to give sperm oil monoalkylolamide sulphosuccinate.

30 The fat charge used in producing the soap component of the new bars is not critical, but it is preferred to use a charge comprising about 50 to 70 percent tallow and 30 to 50 percent of the oils of the coconut type, including coconut oil, palm kernel oil, Babassu oil, and the like. Fatty materials that may be used in the fat charge to the kettle or other equipment for making the soap including the following:

Coconut Oil	Castor Oil
Palm Kernel Oil	Groundnut Oil
Babassu Oil	Linseed Oil
Palm Oil	Cottonseed Oil
Animal Fats	Fish Oils
Olive Oil	and hydrogenated versions of these products, but tallow and coconut type oils are preferred
Tallow Oil	
Resin	

35 40 45 50 55 60 The caustic used to saponify the fat charge is preferably sodium hydroxide but it may be replaced in part by potassium hydroxide, e.g., up to about 15 percent if desired.

It is advantageous to include a preservative and/or a sequestrant in the soap to prevent the rancification of the free fatty acids. Among suitable preservatives and

sequestrants are the following: 2-6 ditertiary butyl p-cresol, tertiary butyl hydroxyanisole, "Sopanox," triphenyl phosphite, stannic chloride magnesium silicate, Benztriazole and the alkali salts of ethylene diamine tetraacetic acid, hydroxyethylethylene diamine triacetic acid, diethylene triamine pentacetic acid and dihydroxyethyl glycine.

The usual steps for converting kettle soap into milled toilet bar form may be used for making the bars of the present invention which include crutching the neat soap phase with the predetermined proportion of synthetic detergent and other desired additives then drying the soap to a moisture content within the range of about 8 to 15 percent, preferably about 9 to 10 percent, mixing the dried soap in the form of dried ribbons, granules, or the like, in an amalgamator with other desired additives such as colors, perfumes, glycerine, lanolin, cold cream, etc., milling the mixture, plodding the milled chips to form a long, continuous bar, cutting the bar into tablet or cake lengths and pressing or stamping the tablet or cake which may then be wrapped or not, as desired.

Suitable soap making processes that may be used to prepare soap for use in the present process include the usual kettle soap making process, continuous saponification processes in which saponification is effected with aqueous alkali and heat, the resultant mixture being washed and fitted to obtain a neat soap either continuously or by use of a kettle for the fitting and optionally one or more washing stages, and neutralization processes for fatty acids derived by hydrolysis of fats and oils.

The kettle process of making soap is well known to those skilled in the soap making art so it will be disclosed here only in general outline since it does not form part of the present invention. A typical kettle process includes the following stages:

1. Killing or saponification stage
2. Change stage
3. Washing stage
4. Fitting or pitching stage

In the first or saponification stage, the fatty material chosen for the particular soap to be produced, e.g., fats and oils which are glycerol esters of fatty acids, is heated with aqueous caustic solution to effect substantial conversion of the fatty material to glycerine and fatty acid salts of the alkali metal or metals present in the caustic solution. For toilet bars, sodium soaps are generally preferred, but in some cases caustic potash may be used with caustic solution. Potassium soaps are softer than sodium soaps of the same fatty acid content and, therefore, the content of potassium fatty acid salts is somewhat limited in proportion to the sodium fatty acids salts in order to have a soap that works up well into bar form in conventional soap-making machinery. Generally, the caustic solution used in the killing stage is obtained in whole or in part from the change stage of another batch. The extent of saponification in the killing stage is not critical and may vary from as low as about 80 percent to almost complete saponification.

In the change stage, which may take place in one or more separate operations, salt is added to the reaction mixture in sufficient concentration to effect precipitation of the soap from the solution. The salt used may be fresh salt or salt recovered from the purification of the glycerine, or a mixture of both. Generally, boiling is continued for a short time after addition of the salt

and if the saponification is incomplete in the killing stage caustic may be included with the salt to complete the saponification during this boil. The mass is then settled, during which the less dense soap rises to the top and the spent lye containing the bulk of the glycerine and electrolyte sinks to the bottom. When the settling is complete the lye is drawn off and sent to the glycerine plant for recovery of the glycerine, salt, etc.

The washing stage has as its object the more complete removal of glycerine, which may be as much as 0.5 percent of the weight of the soap layer left after drawing off the lye, and the complete saponification of the fat charge. In general, a washing operation consists of closing the soap by adding water and boiling vigorously, usually with open steam, and then adding salt and/or caustic to grain the soap and permit settling again into an aqueous lower layer and an upper grained soap layer. Where caustic is used in the washing operation, it is sometimes called a strengthening change and the lye settled is not fully spent and may be used as the caustic solution in the killing stage of another batch of fatty material. The washing operation also removes further amounts of impurities that may have been present in the original charge.

The fitting or pitching stage has for its objective the separation of a neat soap phase from a nigre phase and it is effected by again closing the soap by the addition of water and boiling. The water addition is carefully done so as to reach a final stage where the electrolyte content of the mixture is sufficient to dissolve part of the soap but not all of it. On settling, the dissolved soap sinks to the bottom and forms the nigre while the undissolved soap rises to the top as neat soap. The neat soap may then be pumped from the kettle for further processing.

A typical composition of the withdrawn neat soap is approximately 63 percent total fatty acids, with a maximum of about 0.14 percent caustic calculated as Na₂O and a maximum of about 0.6 percent sodium chloride, with water at about the 30-32 percent level. The water content is typically reduced to approximately 10 percent during further processing.

Soap of similar composition may be obtained by other soap making processes, such as the continuous and neutralization process referred to above. These processes are also well known to workers of ordinary skill in this art and need not be further described.

In further accordance with the invention, the new combination bars comprise a major portion of soap and a minor portion of synthetic detergent by weight. A combination of up to about 30 percent by weight synthetic detergent and not less than about 60 percent by weight soap is preferred. Of course, minor amounts of materials such as pigments, perfumes, sequestrants, etc., that are commonly employed in toilet soap bars may also be included in the new combination bars. Combination bars formulated with these materials and within these limits provide excellent lime soap dispersing characteristics without adversely affecting the lathering performance and feel of the final bar.

Suitable combination bars in accordance with the invention can be prepared as follows (all percentages are by weight):

Sperm oil monoethanolamide sulphosuccinate containing about 40 percent of active ingredient is mixed with a soap base containing about 63 percent total fatty acids and 32 percent moisture, in the following proportion:

tions. The soap base also includes small amounts of preservatives and sequestrants in accordance with principles well known in the art.

Example number:	1	2	3	4	5
Soap base	95.0	90.0	85.0	80.0	75.0
Sperm oil Monoethanolamide sulphosuccinate (40%)	12.5	25.0	37.5	50.0	62.5

The soap base-synthetic detergent mixtures are then dried to about a 10 percent moisture content. The dried mixtures have the following approximate compositions:

Example number:	1	2	3	4	5
Soap	83.7	77.7	71.9	66.3	61.0
Sperm oil Monethanolamide sulphosuccinate	6.3	12.3	18.1	23.7	29.0
Water	10.0	10.0	10.0	10.0	10.0

The dried, soap base-synthetic detergent mixtures are then process by conventional soap making techniques into bar form. A small amount of titanium dioxide, about 0.2 percent, and perfumes and colorants may also be added during the processing of the soap base-synthetic detergent mass into bars.

The soap base-synthetic detergent combination bars of the foregoing Examples 1-5 exhibit lathering characteristics, soil removal properties, mildness and tackiness, not significantly different from similar soap bars formulated without the sperm oil monoethanolamide additive. However, the new combination bars exhibit a very marked reduction in the amount of lime soap curd formed when the bar is used in calcium and magnesium hard water. Variation of the amount of synthetic detergent in the new bar from nil to about 30 percent results in progressively greater lime soap dispersing properties without any significant effect on the lather, soil removing, mildness and other desirable characteristics of the soap portion of the bar.

Panel tests on hand washing performance of combination bars according to the foregoing formulations with the amount of synthetic detergent being nil, 6.3, 12.3, 18.1, 23.7 and 29.0 percent showed no significant difference between the bars for speed and formation of

lather, amount of lather, stability of lather and creaminess of lather. All of the foregoing bars were found to be firm, non-tacky and pleasant to use.

Although the present invention has been described and illustrated with reference to certain specific embodiments, it is to be understood that variations and modifications can be made without departing from the spirit and scope of the invention as defined in the following claims.

10 I claim:

1. An improved detergent bar consisting essentially of:

A. a major amount of an anhydrous water higher fatty acid soap, and

15 B. a lime soap dispersing agent chosen from the group consisting of:

20 wherein m is chosen from the group consisting of sodium, potassium hydrogen, ammonium and ethanamine, R_1 is chosen from the group consisting of hydrogen and C_{12} to C_{20} saturated and unsaturated fatty chains, R_2 is chosen from the group consisting of C_1 to C_4 aliphatic hydrocarbon chains, and R_3 is chosen from the group consisting of C_{15} to C_{19} saturated and unsaturated fatty chains, said lime soap is dispersing agent being present in an amount ranging from a finite quantity sufficient to impart lime soap dispersing properties to the detergent bar composition up to about 30 percent by weight of said bar.
